UNITED STATES PATENT OFFICE.

FREDERICK J. BLATZ, OF WILMINGTON, DELAWARE, ASSIGNOR TO THE PHILADELPHIA TEXTILE MACHINERY COMPANY, OF PHILADELPHIA, PENNSYLVANIA, A CORPORATION OF PENNSYLVANIA.

PROCESS OF DAMPENING LEATHER.

1,352,244.

Specification of Letters Patent.

Patented Sept. 7, 1920.

Application, filed February 14, 1917. Serial No. 148,677.

To all whom it may concern:

Be it known that I, FREDERICK J. BLATZ, a citizen of the United States, and a resident of Wilmington, county of New Castle, 5 State of Delaware, have invented certain Improvements in Processes of Dampening Leather, of which the following is a specification.

The object of my invention is to improve 10 the process of dampening leather prior to certain finishing steps in the treatment of the leather during its manufacture.

Leather after being dyed and dried is hard and it must be conditioned by dampening so that the further finishing processes of 15 ironing or glazing can be carried out without the liability of the leather cracking.

Heretofore, it has been the common practice to dampen the leather by placing the 20 skins on a floor, one upon another, with layers of damp sawdust between the skins, and allowing them to remain from four to twenty-four hours, according to the character of the leather, so as to moisten them 25 sufficiently. In this method, it is impossible to introduce the proper percentage of moisture because of the uneven application of water in dampening the sawdust before using.

30 Another old method is to immerse the leather in warm water for a longer or shorter period, varying from two to ten or more seconds, depending upon the heft of the hide or skin. By this method it is almost impossible to obtain constant, uniform immersion 35 in the water.

In the accompanying drawing:

The figure is a diagrammatic sectional view of a machine for carrying out my 40 process.

It will be understood at the outset that I lay no claim to the particular machine, as this forms the subject of a patent in the name of Elwood B. Ayres, No. 1,259,199, 45 March 12, 1918.

I place the leather *a* on a moving table, or a moving carrier, such as an endless belt 1. This belt is preferably open so as to expose the under side of the leather. Any suitable 50 means may be provided for traversing the leather and both sides of the leather are sub-

jected to a spray of water. This spray can be regulated so as to provide the proper amount of moisture. In the present instance, 55 2, 2 are water pipes and 3, 3 are air pipes, both the water and the air being under pressure, and a series of nozzles 4 are in alignment with the nozzles 5 projecting from the water pipes, the water and air being under the control of suitable valves so as to regulate 60 the amount of water and air and insuring the proper proportions of water and air to produce the best results. It is also possible to use water sprayed by its own pressure without the use of air or steam to vaporize 65 it. An important factor is the use of a heating coil by means of which the temperature of the spray box can be maintained as desired throughout the year. This helps materially to soften the body of the hides or 70 skins, causing them to absorb the water more uniformly and more quickly than heretofore.

I preferably arrange a series of these spraying devices, one located in advance of the other, so that as the leather travels it 75 will be subjected to a series of sprays. It will be understood that while I have shown the spraying devices located in a casing, as at 6, in some instances the leather may be subjected to the action of a spray from a 80 single row of jets and the leather reversed so that both sides can be sprayed. In fact, in some instances, a hand spray can be used without departing from the essential features of the invention.

I preferably heat the interior of the casing and keep it at an even temperature so as to soften the skins in order that they may the more readily receive the moisture. In the drawings, I have shown a series of heating pipes 7, but other means may be used without departing from the spirit of the invention.

By this process the time consumed in dampening leather can be materially shortened and the amount of moisture can also be regulated, insuring a more even dampening than heretofore. Furthermore, this improved process takes up considerably less room than the old process and the sawdust usually employed is dispensed with.

The sand and dirt accumulating in reused

sawdust has always been an added annoyance to the leather finishers. In this process, however, only one-half the labor is required as compared with the process in which sawdust is used.

I claim:

The process of treating leather to effect

dampening thereof, which consists in subjecting the leather, while in a flat condition, to water in the form of fine spray in the presence of heat, whereby the body of the leather may be softened by the combined action of heat and moisture.

FREDERICK J. BLATZ.
